MEANS FOR FORMING WALLS

Gustave Edward Westberg, Los Angeles, Calif.

Application September 30, 1935, Serial No. 42,874

6 Claims. (Cl. 72—16)

This invention relates to building construction and particularly pertains to a method and means of forming walls.

In the construction of buildings it is common practice to provide a back wall and to apply an outer wall thereto and in fixed relation therewith. The outer wall usually incorporates reinforcing elements which are imbedded within the cementitious mixture of the inner wall. 10 This provides a reinforced wall section applied to a relatively rigid backing. Such a construction has been found to be especially desirable in sections of the country where earthquakes occur, since the wall structure affords some 15 flexibility while remaining stable. Structures of this type are also desirable where it is necessary to remodel or repair building structures. In forming wall structures of this type it is necessary to provide means for rapidly and 20 accurately determining wall thicknesses since in most instances the cementitious material is applied to the backing by pressure gun apparatus which applies the cement mix in a finely divided hydrated state until a sufficient thickness 25 of the material has accumulated on the packing to provide a desired wall structure. Heretofore guide means have been used which are subject to tension and are liable to become dislodged, or disarranged, during the time the 30 cementitious material is being applied. It is the principal object of the present invention therefore to provide means whereby the thickness of the wall may be determined readily and whereby the guide means may be accurately and 35 rigidly supported during the entire wall construction operation, and may be thereafter easily removed.

The present invention contemplates the provision of supporting members applied to the 40 wall reinforcing elements and carrying guide members by which the thickness of cementitious material may be determined and maintained.

The invention is illustrated by way of example in the accompanying drawing in which:

45 Figure 1 is a view in elevation indicating the application of the present invention to the reinforcing elements of the wall structure.

Fig. 2 is a view in horizontal section through the wall structure as seen on the line 2—2 of Fig. 1 and discloses in detail the construction with which the present invention is concerned.

50 Fig. 3 is an enlarged fragmentary view showing an end of a supporting bracket as seen on the line 3—3 of Fig. 1.

55 Fig. 4 is an enlarged fragmentary view in

elevation showing the manner in which a supporting bracket receives a guide element.

Referring more particularly to the drawing, 10 indicates a backing wall. This wall may be of any desired construction, and may be of frame, masonry, or cement. Disposed in a plane parallel to the surface of the wall 10 and suitably spaced therefrom is a reinforcing structure, such, for example, as the horizontally extending reinforcing rods 11 and the vertically extending 15 rods 12. These rods are tied together in any commonly accepted manner and are spaced from the face of the wall to provide an intermediate space 13. Applied to the rods 11 and 12 at intervals throughout their lengths 15 are ground wire brackets 14. These have straight portions 15 which extend longitudinally of a reinforcing element and are preferably fastened thereto by wires 16 and 17. At one end of the straight portions an outwardly extending 20 arm 18 occurs. This arm is formed as a continuation of the straight portion of the bracket and terminates in a curved end 19 as indicated in Fig. 3 of the drawing. A serration is cut across the top face of the curved end 19 to 25 form a V-shaped seat 20 and a serration is formed upon the diametrically opposite side of the bracket to form a V-shaped groove 21 of relatively smaller size. The V-shaped seat 20 receives a transversely extending ground wire 30 22 which is stretched across a plurality of the ground wire brackets and seats concentrically in the V-shaped seats 20 of these brackets. The opposite ends of the ground wires 22 are secured around the shank of anchor nails 23 35 which when driven into the backing wall 10 will draw the ground wires tightly across the free ends of the brackets. Attention is directed to the fact that the extensions 18 of each of the ground brackets may be sufficiently flexed to 40 produce any desired spacing of the ground wires with relation to the plane of the reinforcing members 11 and 12 and the back wall 10. In this manner it is possible to insure that when the reinforcing members 11 and 12 are in fixed 45 relation to the back wall 10, the application of the brackets to the reinforcing members and the adjustment of the brackets will make it possible for the thickness of the wall to be readily 50 gauged. The ground wires are held in their seated positions at the ends of the brackets by wires 24 which wrap around the wires and the brackets and may be twisted into the grooves 21. 55

In operation of the present invention the rein-

forcing bars 11 and 12 are suitably spaced from the face of the backing wall 10, after which the ground wire brackets 14 are secured at intervals as the dictates of the mechanic may determine. The brackets may be applied to both reinforcing elements 11 and reinforcing elements 12 in which event ground wires 22 may be strung vertically and horizontally and fastened to the nails 23. The extension portions 18 may be bent as desired, after which the nails may be driven into the wall 10 to create any desired degree of tension on the ground wires 22. When this has been accomplished, cementitious material may be applied to the backing wall 10 until it has accumulated on the backing wall to the level indicated by the dotted line 25 in Fig. 2 of the drawing. When the cementitious material has accumulated to this level, a wall section 26 will be formed on the face of the wall section 10, said section being of uniform thickness and reinforced. The ground wires 22 may then be taken away so that any desired surface can be thereafter applied to the outer face of the wall portion 26. 25 It will thus be seen that by the method here described and the structure here shown that a reinforced wall structure may be readily set up and a reinforced wall of a desired thickness accurately applied. 30 While I have shown the preferred form of my invention as now known to me, it will be understood that various changes might be made in the combination, construction, and arrangement of parts by those skilled in the art, without departing from the spirit of the invention as claimed.

Having thus described my invention, what I claim and desire to secure by Letters Patent is:

1. Means for gauging the thickness of a wall 40 to be made by the accumulation of cementitious material against a backing and around reinforcing elements, said means comprising brackets secured to said reinforcing elements, the outer ends of said brackets terminating in a plane 45 parallel to that of the reinforcing elements and spaced therefrom, guide wires rigidly secured at their opposite ends and stretched across said brackets to be held thereby in spaced relation to the reinforcing elements whereby when the cementitious material has accumulated on the backing to a plane coincident with the guide wires the desired wall thickness will be made.
2. Means for gauging the thickness of a wall 55 to be made by the accumulation of cementitious material against a backing and around reinforcing elements, said means including a bracket having a shank adapted to be fastened to a wall element, an outwardly extending portion at one end of said shank adapted to be set with its outer end in a desired offset relation to the plane of the shank, and a ground wire adapted to be strung across the end of said bracket to

be held in spaced relation to the plane of the shank of the bracket.

3. Means for gauging the thickness of a wall to be made by the accumulation of cementitious material against a backing and around reinforcing elements, said means including a bracket having a shank adapted to be fastened to a wall element, an outwardly extending portion at one end of said shank adapted to be set with its outer end in a desired offset relation to the plane of the shank, and a ground wire adapted to be strung across the end of said bracket to be held in spaced relation to the plane of the shank of the bracket, said free end of the bracket being formed with a seat across which the ground wire lies.

4. Means for gauging the thickness of a wall to be formed by the accumulation of cementitious material against a false frame and around reinforcing elements, said means comprising reinforcing elements erected in spaced relation to the false frame, brackets secured to the reinforcing elements, the outer ends of said brackets terminating in a plane parallel to the reinforcing element and spaced therefrom, guide wires 25 secured at their opposite ends and stretched across said brackets to be held thereby in spaced relation thereto, whereby when the cementitious material has accumulated on the false frame to a plane parallel to the guide 30 wires the wall will have attained the desired uniform thickness.

5. Means for gauging the thickness of a wall to be formed by the accumulation of cementitious material against a backing and around reinforcing elements, said means including a bracket for a shank adapted to be fastened to a wall element an outwardly extending portion at one end of said shank adapted to be set with its outer end at a desired offset relation to the plane of the shank, and a ground wire adapted to be strung across the end of said bracket to be held in spaced relation to the plane of the shank bracket, said free end of the bracket being formed with a seat across which the ground wire lies, and means whereby the ground wire may be removed when the desired uniform accumulation of cementitious material is attained.

6. Means for gauging the thickness of a wall to be made by the accumulation of cementitious material against a backing, said means comprising the erection of a reinforcing structure in a plane vertical to the wall and in spaced relation thereto, guide members secured to the reinforcing structure and terminating in a plane parallel thereto, guide members securely fastened at their opposite ends and stretched across said guide elements whereby the wall will have attained the desired thickness when the outer surface of cementitious material reaches a plane coincident with the guide members.

GUSTAVE EDWARD WESTBERG.
